UNITED STATES PATENT OFFICE.

CHARLES ANDERSON CASE, OF NEW YORK, N. Y., ASSIGNOR, BY MESNE ASSIGNMENTS,
TO ORE DESULPHURIZATION COMPANY, A CORPORATION OF NEW YORK.

TWYER.

982,244.

Specification of Letters Patent. Patented Jan. 24, 1911.

Application filed October 11, 1909. Serial No. 521,973.

To all whom it may concern:

Be it known that I, CHARLES ANDERSON CASE, a citizen of the United States, and a resident of the borough of Manhattan, in the county of New York and State of New York, have invented certain new and useful Improvements in Twyers, of which the following is a specification.

This invention relates to a twyer for furnaces by means of which superheated steam or a mixture of superheated steam and air or a mixture of oil, super-heated steam and air may be supplied to a furnace or other apparatus for desulfurizing ores, and for other purposes.

In the accompanying drawings Figure 1 represents a vertical section of an ore desulfurizing furnace, with a pair of the twyers attached thereto, Fig. 2 shows an enlarged partial vertical axial section of the twyer and a fragmental sectional portion of the furnace represented in Fig. 1, Fig. 3 is a section of Fig. 2 on the line 3, 3, Fig. 4 represents an enlarged front view of the twyer with a portion of the furnace, Fig. 5 represents a partial left hand end view of Fig. 4, Fig. 6 shows an enlarged section of Fig. 4 on the line 6, 6, Fig. 7 is a section of Fig. 4 on the line 7, 7, and Fig. 8 shows a partial right hand end view of Fig. 4.

The furnace shown and described with this specification is claimed in an accompanying application filed herewith.

The drawings show a charging hopper 20 having the sliding gates 21, 22 at the lower end thereof, and below which is located the inclosed water jacketed furnace 23. The furnace is provided with the head 24 having openings 25 that lead to fume piping 26, and the opening 27 for the hopper 20. The furnace has fitted thereto the water jacketed twyer supports 30. Water piping 31 leads into the latter and water outlet piping 32 extends from the furnace, while pipe connections 33 connect the water jackets of said supports with the water jackets of the furnace.

Each water jacketed twyer support 30 has a circular threaded opening 35 at one side and conduits 36 connect the upper and lower portions at the opposite side thereof, and which constitute water protecting bars to prevent the ore entering the twyer.

The lower end of the furnace 23 is sup-

ported on a frame 40, which has connected 55 up therewith the inclined discharging chutes 41 and the adjustable swinging chutes 42. The latter are inclined to different positions by means of the screw rods 43. Framing 46 supports the frame 40 and also the 60 cooling hopper 47. Discharging drums 48 are journaled in the cooling hopper and a conveyer 49 is located at the bottom thereof.

In each threaded opening 35 of the twyer supports is secured the outer barrel 55 of 65 the twyer, which at its outer end carries the ring 56. The latter has formed therewith the threaded ends 57, 58 of the same internal diameter and an inwardly extending flange 59. An inner annular port 60 is formed 70 with said ring. The engagement of the barrel 55 and ring 56 is made secure by the engagement of the threaded end 57 with a corresponding thread on the said barrel. Steam inlet piping 65 with the valve 66 is connected with the said annular port 60 at the upper end thereof, and drain piping 67 with the valve 68 is connected with the lower end of said port. Drain piping 69 extends from the lower end of the outer barrel 55 75 and is connected with the valve 68 by means of the piping 70. The space between the barrel 55 and chamber 75 to be described, constitutes the annular super-heating chamber 71.

A combustion chamber 75 within the barrel 55 has one end supported on the flange 59. An igniting barrel 76 with the tapering sleeve 77 of fire clay and the like is supported in the threaded end 58 of the ring 56. A 90 funnel cap 80 is connected to the outer end of the sleeve 76, and has extending from the lower portion thereof the bracket 81. The latter supports a fuel chamber 82, threaded on its outlet end for the adjustable damper 95 83, that can be located on different portions of the outer surface of said fuel chamber 82, to control the volume of air drawn into the funnel cap 80. Fuel gas inlet piping 84 with the valve 85 is connected to the fuel 100 chamber 82. A burner 88 with the chambers 89 and 90 has connected thereto the needle valve 91 having handle 92. An outer nozzle 93 extends from the chamber 89 and a concentric inner nozzle 94 extends from the 105 chamber 90. The said nozzles both extend into the fuel chamber 82. Steam piping 95 with the valve 96 connects with said cham-

ber 89, and oil piping 97 with the valve 98 connects with the chamber 90.

- To use the twyer fuel gas is forced through the piping 84, enters the fuel chamber 82 around the outside of the outer nozzle 93, and from thence enters the twyer. At the same time steam in the piping 95 enters the outer nozzle 93, mixes with the fuel gas in the chamber 82 on its way to the twyer.
- 10 Oil is also forced to the twyer by means of the piping 97, the port of the needle valve 91, and the inner nozzle 94. The whole charge is mixed in the sleeve 77 in the igniting barrel 76 from which it enters the combustion chamber 75. On leaving the latter the charge is mixed with steam, which has entered through the piping 65 and has been super-heated in the super-heating chamber 71.
- 20 Having described my invention what I desire to secure by Letters Patent and claim is:—
- 25 1. In a twyer the combination of a combustion chamber and a steam superheating chamber connected therewith.
  - 30 2. In a twyer the combination of a combustion chamber, a steam super-heating chamber connected therewith, means to supply fuel to the combustion chamber and means to supply steam to the super-heating chamber.
  - 35 3. In a twyer the combination of a combustion chamber, an annular steam superheating chamber connected therewith, means to supply steam to said super-heating chamber, means to drain the super-heating chamber, means to supply fuel to the combustion chamber, and adjustable means to control

an air supply to the said combustion chamber.

40

- 45 4. In a twyer the combination of a combustion chamber, a super-heating chamber connected therewith which derives its heat from said combustion chamber, a fuel chamber for said combustion chamber, an adjustable damper to regulate the volume of air for said combustion chamber carried on the fuel chamber, a burner for the fuel chamber, an oil chamber and a steam chamber in the burner, oil piping connected with the said oil chamber, steam piping connected with the said steam chamber, an inner nozzle connected with a port in the oil chamber, a needle valve for said port, an outer nozzle concentric with the inner nozzle and connected with said steam chamber.

45

- 50 5. In a twyer the combination of a combustion chamber, an igniting barrel connected therewith, a fuel chamber adjacent to the igniting barrel to discharge fuel into the latter, an adjustable damper on the fuel chamber to regulate the volume of air forced into the igniting barrel and combustion chamber, a burner for the fuel chamber, a pair of nozzles on the burner extending into the fuel chamber, an outer barrel concentric with the combustion chamber, and steam inlet piping and drain piping connected to the outer barrel.

60

Signed at the borough of Manhattan in 70 the county of New York and State of New York this 9th day of October A. D. 1909.

CHARLES ANDERSON CASE.
